UNITED STATES PATENT OFFICE

GUSTAVE A. NEW, OF PORT CLINTON, OHIO, ASSIGNOR TO AMERICAN GYPSUM COMPANY, OF PORT CLINTON, OHIO, A CORPORATION OF OHIO

GYPSUM WALL BOARD

Application filed May 20, 1929. Serial No. 364,478.

This invention relates to improvements in gypsum wallboard, and more particularly to an improved gypsum wall covering material and process for making the same.

5 In a previous application filed by me on March 26, 1928, Serial No. 264,658, which issued as Patent No. 1,787,163 December 30, 1930, I disclosed a construction and process for manufacturing gypsum wallboard where-
 10 in the edges of the board were reinforced by a fabric strip which was folded into the desired cross-sectional contour and fed between the edges of the covering sheets during the process of making the board, with the result that
 15 one folded portion of the strip was embedded in the plaster body and other portions extended over the edge faces of the plaster and were sealed thereto by the penetration of the plaster through the meshes of the fabric.
 20 The purpose of the present invention is to provide an improved product having woven fabric adapted to reinforce the edges as well as an improved method for folding and incorporating the folded material into the
 25 board during the course of its manufacture, as a part of a continuous process, such as is now generally employed in the plaster board industry.

A further object of the invention is to pro-
 30 vide plaster or wallboard wherein the fabric applied to the edges thereof assumes not only a T-form in sectional contour but is of double thickness throughout.

A further object of the invention is to pro-
 35 vide a wallboard the edges of which are reinforced by a strip of woven fabric so folded and applied that its edges are embedded in the plaster body of the wallboard.

A further object of the invention is to pro-
 40 vide a novel and practical method of folding the reinforcing material into a so-called double T-form in which the edges of the un-
 folded reinforcing strip are brought together to form the base of the T and are thence fed into the edge of the board and embedded in the plaster or like material.

A preferred embodiment of my invention is disclosed in the accompanying drawings, in
 45 which

Figure 1 is a vertical cross section of one

edge portion of the finished board showing the disposition of the reinforcing material.

Figure 2 is a perspective view of a frag-
 55 ment of the finished product showing more clearly the disposition of the edge reinforce-
 ing material.

Figure 3 is a perspective view of a strip of reinforcing fabric showing the successive steps in folding the strip from its initial to its final T-shape, and

60 Figures 4 to 8 are sectional views of the fabric strip taken at several successive points during the folding operation as indicated by lines 4—4 to 8—8 respectively in Figure 3.

The following is a description of the prod-
 65 uct made in accordance with my invention, together with a practical method of manu-
 facturing the same.

As shown in Figures 1 and 2, the plaster or
 70 wallboard consists of a central core or body 1 of plaster, i. e., calcined gypsum or other suitable material interposed between two cov-
 ering sheets 2, 2 of fibrous material prefer-
 ably paper of the kind and quality generally
 employed for the purpose. The two sheets 75
 are of the same width and terminate flush
 with the edge face of the plaster body 1, so
 that in the absence of edge reinforcing means,
 the product would have all of the character-
 80 istics of the so-called raw or trowelled edge
 plaster board. The finished product may be
 considered to be $\frac{3}{8}$ of an inch in thickness,
 which is the standard thickness for general
 purposes.

As already indicated, the edge faces of the
 85 plaster body are reinforced by woven fabric
 in the form of a strip 3 which has been folded
 lengthwise into T-form, the cross member
 portion 3a extending between the covering
 sheets 2, 2 and perpendicular thereto, and the
 90 stem portion 3b extending edgewise into the
 body 1, between the covering sheets 2, 2. The
 reinforcing material, as folded, is of dou-
 ble thickness throughout both portions 3a
 and 3b.

The material preferably used for the edge
 95 reinforcing is a relatively inexpensive woven
 fabric of a fairly open mesh which can be
 readily obtained on the market in rolls of
 the desired width. This fabric preferably
 100

should be treated with a suitable adhesive or sizing to give it a certain stiffness which will permit it to hold its shape better after folding and creasing. Due to its loosely woven texture it follows that it is capable of being intimately incorporated with the plaster body 1 inasmuch as the plaster in its wet or plastic state can pass or be forced into the meshes of the fabric, thereby affording a secure bond 10 between the two materials.

Referring now to a practical method of folding the fabric, Figures 3 to 8 illustrate the various steps or folding operations through which the fabric is carried in its 15 progress from its original flat form to its final T-shape. It will be understood in this connection, that the folding of the fabric is a continuous operation carried on in conjunction with the manufacture of the plaster or 20 wallboard on a continuous process machine of any standard and approved design. To apply my reinforcing material such a machine could be equipped with any suitable feeding and folding devices, although the apparatus 25 preferably used is that disclosed in a co-pending application filed by myself.

In Figure 3, the material may be assumed to advance from left to right, being fed or 30 unwound from a roll and travelling in a substantially straight line toward the portion of the wallboard machine where the two cover sheets 2, 2 and the intermediate layer of wet plaster 1 pass between pressure rolls and are reduced to the form of the finished product.

35 The fabric leaves the roll as a flat strip, Figure 4, and preferably in a vertical plane. Immediately upon leaving the roll, it passes through a suitable folder which arches it transversely throughout its central portion as 40 shown in Figure 5. The strip is then led into contact with a suitable forming block or mandrel having three faces arranged at right angles to each other and around which the strip is folded and creased, giving it the 45 square U-shape shown in Figure 6. For convenience the several portions of the strip may now be indicated by letters thus: a base portion a and two edge portions a' , a' of equal width, folded at right angles to the base portion a . Coacting with this block are suitable 50 pressure members which act to crease the strip of material along lines b , b , thus establishing the width of the cross portion of the T-section to be ultimately formed. On leaving the 55 forming block the strip, retaining its square U-shape, is led to another folding device which first brings the outer margins of the edge portions a' , a' of the U-shaped strip together and bends the remaining edge portions 60 toward each other, forming a somewhat triangularly shaped section as shown in Figure 7. As the strip advances, the edge portions a' , a' of the strip are gradually brought together, the portions thereof adjacent the base 65

a being simultaneously folded inwardly and over upon the base a .

The edge portions a' , a' are now L-shaped and located in back to back relation, thus providing a double thickness of the material throughout the entire cross section of the folded reinforcing strip as shown in Figure 8. All of the folds of the strip are finally creased so that the folded strip will hold its T-shape. 75

Having completed the final forming and creasing of the strip, it is then fed by means of suitable guides toward the pressure rolls of the wallboard machine and thence into position between the covering sheets 2, 2 substantially at the point where they pass between said rolls. The folded strip 3 is disposed edgewise, with the cross portion $3a$ of the T vertical and parallel to the plane of the edge of the face of the wallboard and the stem portion $3b$ extending horizontally into the body of plaster. 80

It will be understood that both edges of the plaster board may be treated in the same manner by the feeding of two continuous strips 90 into the opposite side edges thereof.

This method of reinforcing the edges of plaster board or the like may be used to reinforce the edges of any sheet or board, with or without covering sheets, the body of which is composed of a setting or hardening material. It will be evident to those skilled in the art that my T-shaped fabric reinforcing strips may be used to reinforce the edges of numerous types of sheets which are made by rolling plastic material into sheet form and allowing it to harden and therefore I do not limit my invention to the specific type of sheet described in this specification and illustrated in the drawings. 95

Having set forth a preferred embodiment of my invention, I claim:

1. A wallboard comprising a plaster body, covering sheets on opposite sides of said body, and a strip of woven material folded in T-section of double thickness and applied along the edges of said body, with a portion thereof embedded edgewise in the body. 100

2. A wallboard comprising a plaster body, covering sheets on opposite sides of said body, and a strip of woven material folded lengthwise into angularly disposed portions of double thickness and applied to the edge portions of the body so that said strip of woven material is embedded in said body. 115

3. A wallboard comprising a plaster body, covering sheets on opposite sides of said body and terminating at the side edges thereof, and a strip of woven reinforcing fabric folded lengthwise upon itself to form portions of double thickness arranged in T-form, one portion being applied parallel to the edge face of said body and the other portion at right angles to said edge face. 120

4. A wallboard comprising a plaster body, covering sheets on opposite sides of said body and terminating at the edge faces thereof, and a strip of woven fabric folded upon itself the U-shaped strip into T-shape and creasing the same along the fold lines, and feeding the T-shape strip into the edge of the advancing cover sheets and wet plaster.
- 5 to form portions of double thickness arranged in T-form, one portion being positioned in said plaster body parallel to the edge face of said body substantially flush with the edges of the covering sheets and the other portion 10 extending into said body at right angles to said first named portion.
6. A process of reinforcing the edges of wallboard in the course of manufacture, consisting of feeding a strip of reinforcing material toward the edges of the board, folding the advancing strip longitudinally into portions of double thickness arranged in T-form, and guiding the folded strip into the edge of the board.
7. A process of reinforcing the edges of gypsum wallboard in the course of manufacture, consisting of feeding a strip of woven fabric toward the edges of the board, folding the advancing strip longitudinally into angularly disposed portions of double thickness of the material, and feeding the folded strip into the edge of the board with one portion parallel to the edges of the body of the board and the other portion extending edge- 20 wise into said body.
8. A process of manufacturing wallboard consisting of advancing continuous sheets of covering material toward a pair of pressure rolls, feeding wet plaster between said sheets in advance of said pressure rolls, feeding strips of edge reinforcing material toward the edges of said advancing sheets, folding said strips lengthwise into portions of double thickness and arranged in T-form, and guiding the folded strips between the edges of the covering sheets with one portion embedded parallel to the edge face of the plaster and the other portion embedded edgewise therein.
9. A process of manufacturing wallboard consisting of advancing continuous sheets of covering material toward a pair of pressure rolls, feeding wet plaster between said sheets in advance of said pressure rolls, feeding strips of fabric toward the path of the edges of said advancing sheets, folding the strip longitudinally into U-form, thence folding the U-shaped strip into T-shape and creasing the same along the fold lines, and feeding the T-shape strip into the edge of the advancing cover sheets and wet plaster.
10. A process of manufacturing wallboard 70 consisting of advancing continuous sheets of covering material toward a pair of pressure rolls, feeding wet plaster between said sheets in advance of said pressure rolls, feeding strips of fabric toward the path of the edges of said advancing sheets, folding the strip longitudinally into a square U-form and creasing the same along the fold lines, thence folding and creasing the edge portions of the U-shaped strip to form angularly disposed 75 portions of double thickness arranged in T-form, and feeding the strip thus folded between the edge of the advancing cover sheets with the cross portion of the T-shape strip reinforcing the edge face of the plaster and the stem portion extending edgewise into the plaster.
- In testimony whereof I hereunto affix my signature this 10th day of May, 1929.
